UNITED STATES PATENT OFFICE.

JAMES BYERS, OF CHICAGO, ILLINOIS.

GAS-BURNER.

1,352,351.

Specification of Letters Patent. Patented Sept. 7, 1920.

Application filed October 21, 1919. Serial No. 332,157.

To all whom it may concern:

Be it known that I, JAMES BYERS, a citizen of the United States, residing at Chicago, in the county of Cook and State of Illinois, have invented new and useful Improvements in Gas-Burners, of which the following is a specification.

This invention relates to burners for use in gas furnaces and the like, and has for its object the provision of a burner structure which uses both gas and air, means being provided for imparting to the column of air a whirling movement and other means being provided for causing the exit of the gas at an angle with respect to the movement of the air whereby the discharging air will exert a sucking action on the gas which will to a great extent counter-act the pressure of the gas and consequently cause a short compact flame which will be intensely hot.

An important object is the provision of a device of this character with which may be used pre-heated air under normal or higher pressure, as preferred.

An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings in which—

Figure 1 is a side elevation of the burner,
Fig. 2 is a longitudinal sectional view,
Fig. 3 is an elevation of the tip member, and

Fig. 4 is a cross sectional view on the line 4—4 of Fig. 2.

Referring more particularly to the drawings, the numeral 10 designates a body which may be formed as a casting and which is provided internally with a partition 11 defining air and gas compartments 12 and 13, respectively. The body 10 is provided with holes 14 and 15 communicating respectively with the air and gas chambers 12 and 13. At its sides the body 10 may be provided with lateral extensions 16 to provide securing means.

Threaded into a hole in one side of the body 10, this hole communicating with the chamber 12, is a cylindrical tube 17 and

threaded into a hole in the partition 11 and communicating with the chamber 13, is a pipe 18 which extends co-axially through the tube 17 and which terminates short of the outer end thereof. By this construction it will be seen that the annular space 19 is provided between the tube 17 and pipe 18 and that this space communicates with the chamber 12.

Threaded upon the outer end of the pipe 18 is a tip 20 which has its outer end closed, as shown at 21, and this outer closed end is provided with a circular series of holes 22 which are inclined at an angle of 45° with respect to the longitudinal axis of the members 17 and 18. These holes 22 are the gas discharge openings. Formed integrally around the inner periphery of the tip 20 are spirally arranged ribs or vanes 23 and the spaces between these ribs or vanes are for the passage of air.

In the operation of the device it will be seen that when air and gas are supplied to the burner, the gas will pass through the pipe 18 and out through the holes 22 and the air will pass through the annular space 19 and between the ribs or vanes 23, the air being given a whirling motion owing to the spiral arrangement of the ribs. This whirling column of air upon meeting the gas discharging from the holes 22 will result in thorough mixing of the air and gas so that complete and proper combustion will occur. It will also be apparent that owing to the angularity of the holes 22 the out-rushing air will cause a somewhat sucking effect upon the gas which will result in counter-acting more or less the pressure of the gas which will result in a short and rather fat flame.

From the foregoing description and a study of the drawing it will be apparent that I have thus provided a simple device of the character specified which consists of the minimum number of parts, which will therefore be inexpensive in manufacture, not liable to derangement, and which will yet perform all the functions for which it is intended.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising a body provided with air and gas chambers having inlet openings, a tubular member connected with said body and communicating with the air chamber therein, a pipe extending concentrically through said tubular member and communicating 5 with the gas chamber, and a tip on the end of said pipe having its outer end closed, said closed end being provided with a plurality of gas discharge holes and the outer periphery of said tip being provided with a plurality of spirally arranged ribs defining spiral passages through which the air passes, the air being thereby given a circular 10 motion.
- 10 15 2. A device of the character described

comprising a body provided with air and 20 gas chambers having inlet openings, a tubular member connected with said body and communicating with the air chamber therein, a pipe extending concentrically through 25 said tubular member and communicating with the gas chamber, and a tip on the end of said pipe having its outer end closed, said closed end being provided with a plurality 30 of gas discharge holes and the outer periphery of said tip being provided with a plurality of spirally arranged ribs defining spiral 35 passages through which the air passes, the air being thereby given a whirling motion, said gas discharge holes being at an angle with respect to the longitudinal axis of the gas conducting pipe.

In testimony whereof I affix my signature.
JAMES BYERS.
